UNITED STATES PATENT OFFICE.

FREDERICK E. BENTLEY, OF MAPLEWOOD, MISSOURI, ASSIGNOR OF ONE-FOURTH TO
B. W. FRAUENTHAL, ONE-FOURTH TO A. S. JOHNSON, AND ONE-FOURTH TO T. T.
BURLINGAME, ALL OF ST. LOUIS, MISSOURI.

TELEPHONE INSTRUMENT.

1,219,620.

Specification of Letters Patent. Patented Mar. 20, 1917.

Application filed November 29, 1915. Serial No. 63,971.

to all whom it may concern:

Be it known that I, FREDERICK E. BENTLEY, a citizen of the United States, residing at the city of Maplewood, county of St. Louis, State of Missouri, have invented a certain new and useful Improvement in Telephone Instruments, of which the following is a full, clear, and exact description, such as will enable others skilled in the art to which it appertains to make and use the same, reference being had to the accompanying drawings, forming part of this specification.

This invention relates broadly to telephony and more specifically to a special form of telephone instrument which includes a transmitter and a receiver mounted together as a unitary structure and specially equipped to operate as an amplifying or loud speaking telephone.

I am aware that heretofore various amplifying attachments have been devised for connection to the receiver, and I am also aware that a receiver and a transmitter have been structurally united. The structural arrangement of my device, however, is essentially different from the devices heretofore designed, and the operation of and results obtainable with my device are much superior to the performances of former devices, particularly with respect to the clearness of reproduction, the freedom from disturbing influences and the convenience and ease of manipulation.

The principal object of my invention, therefore, is to provide a special form of telephone instrument adapted to operate as a loud speaking telephone and in which the receiver and transmitter are structurally combined in a unitary instrument.

A further object of my invention is to provide a form of loud speaking telephone wherein the receiver is so associated as to be protected and free from disturbing influences, either electrical or mechanical, arising either from conditions in the transmitter or contingent upon the customary use of the instrument.

A further object of my invention is to provide a structure in which transmitter

and receiver are combined in such fashion as to form an instrument most convenient to certain telephonic uses.

My invention further resides in the provision of various special parts the form and construction of which respectively are such as to make them most efficient in their various individual uses.

Other and further objects of my invention will be obvious or pointed out hereinafter.

In many fields of telephone use, loud speaking receivers and instruments wherein there is no necessity for removing the receiver from the hook, are of exceptional utility. Such for instance is the field of train despatching, wherein messages must be delivered rapidly and communication between the despatching and receiving points established immediately. In such use the ringing or preliminary calling of the point of destination, and the operations at the points of destination incident to cutting the receiver into the line may well be obviated by the use of a loud speaking receiver which is constantly closed across the line. In such an arrangement, of course, messages transmitted from any one of the instruments on the line will be heard in all of the receivers on the line, a feature of importance in many fields of telephone use, inasmuch as all of the operators at the receiving stations are kept advised as to all intelligence transmitted, and hence, as in the case of train despatching, all operators will be kept advised as to all train movements directed or reported.

Heretofore the use of the loud speaking telephone has not proved successful in fields such as that of train despatching, nor has the operation of such instruments heretofore proved agreeable to operators. Two factors contribute to this lack of success—actual physical inconvenience in the use of the instrument, and poor reproduction. The physical inconvenience arises in many instances from the structural separation of the transmitter from the receiver, and the latter being due to various interfering influences such as mechanical vibrations in the horn which tend to set up an audible resonance.

therein, and a vibration in the receiver which operates to set up a hum or harmonic therein similar to the sound of the familiar "howler". I find that these affecting vibrations, when the receiver is structurally connected with the transmitter, may be caused by the vibrations of the transmitter, transmitted through the rigid framework of the instrument. I also find that these resonant vibrations in the amplifying horn may be occasioned by casual vibrations in the receiver other than the irregular reproducing vibrations of the receiver diaphragm, which casual vibrations are imparted through rigid connections between the receiver casting and the horn. These casual vibrations in the receiver may arise from a number of different causes, among which may be mentioned speaking or blowing into the amplifying horn. In the instrument forming the subject matter of my invention, I provide a construction wherein both of these drawbacks are eliminated and whereby essentially new and useful results are obtained.

25 The accompanying drawings illustrate embodiments of my invention—

Figure 1 being a perspective view of one form of instrument embodying my invention;

20 Fig. 2 a front view of the upper portion of a receiver horn therein employed;

Fig. 3 is a detail illustrating the connection between the receiver horn and its supporting parts;

35 Fig. 4 a vertical sectional view of the instrument showing certain of the standard equipment thereof in diagrammatic form;

Fig. 5 a detail illustrating part of the connection between the receiver and the receiver horn;

40 Fig. 6 a side view partly in section of a modified form of my invention;

Fig. 7 a front view of the horn employed therein.

45 Referring to the drawings in detail, numeral 1 indicates generally a standard or support forming a part of the instrument and comprising a base portion 2 and a barrel portion 4 extending from the base portion.

50 This standard is of hollow metal construction and is closed at the bottom of the base portion by a closure 5 removably secured in place and designed to support various elements of the equipment such as the switch 6 hereinafter to be described, the induction coil 7, the condenser 8, etc. Adjacent the upper extremity of the barrel portion is a collar or clamp 9 arranged to adjustably support the transmitter 10 at one side of the barrel portion.

60 The electrodes of the transmitter are connected in the customary transmitter circuit 11, the wires leading into the barrel portion through an aperture fitted with a bushing 12.

65 Removably supported on the standard is

the receiver horn 14. This is a tapering tubular member having a bell or hood portion 15, and a shank portion 16 extending angularly relative to each other, the latter increasing gradually in diameter from its lower end toward the former, and the former flaring out rather abruptly in both transverse dimensions from its junction with the latter. The horn is disposed on the standard so that the shank portion projects down into the barrel portion 4, and the hood portion extends forwardly over the transmitter 10. Immediately above the transmitter, the lower wall of the hood portion is bent reentrantly upon itself toward the top wall forming a convolution 17 which partially divides the hood portion substantially into two lateral parts. At the lower end of the horn is supported the receiver 18, which receiver is of the watch-case form and construction commonly employed in customary practice, except that the usual ear piece is replaced by a screw cap 19 adapted to clamp the diaphragm in the customary fashion, and having a centrally arranged short tubular projection or sleeve 20 projecting therefrom and encircling the sound aperture in the center of the cap. The receiver is suspended from the small or lower end of the horn by means of a flexible sleeve 21, such as of rubber tubing, one end of which encircles and retains the sleeve 20, and the other end of which encircles and is retained upon the lower end of the horn. A curtain 22 of gauze or similar material is disposed to cover the lower end of the horn, to effectively prevent the passage of foreign material from the horn into the receiver, while permitting transmission of vibrations from the receiver diaphragm. Light and flexible springs 24 are attached to the receiver and have upwardly extending portions which are clamped against the rubber sleeve 21 over the end of the horn by any suitable securing means such as the wires 25. The coils of the receiver are connected in the customary secondary or receiver circuit including the condenser 8 and the secondary coils of the induction coil 7. The connection of the receiver to the horn, while such as to provide a cushioned suspension, the sleeve 21 possessing such flaccidity as to prevent the transmission to the receiver of such vibrations or mechanical disturbances as are competent to set up a harmonic vibration in the receiver diaphragm. The springs 24, while having the proper tensile strength to form a secure connection between the horn and the receiver, do not have sufficient rigidity to transmit such vibrations to the receiver, nor are they in actual contact with the horn.

In order to prevent the transmission of disturbing vibrations from the standard to the horn, I provide a flexible connection in

the form of the collar 26, in the nature of a rubber ring or rubber tube, which is disposed in an annular groove about the upper end of the barrel, and which is adapted to 5 receive the shank portion of the horn and provide a supporting bearing for the horn upon the standard while holding the horn actually apart from contact with the standard. In this fashion, the horn is mechanically insulated from any vibrations in the standard which will be competent to affect the receiver or set up a resonant vibration in the horn, the flaccidity of the rubber collar operating to damp out such vibrations. In 10 Fig. 3 is illustrated an arrangement for preventing unintentional removal of the horn from the standard. On the sides of the standard are mounted rather stiff spring clips 29 having their upper ends extended 15 above the upper ends of the barrel, and deflected inwardly to form engaging lugs. On the horn, a distance above the upper end of the barrel, is disposed an annular collar 30. When the horn is placed in the barrel the 20 springs 29 are sprung outwardly to permit the passage of the collar, and then allowed to spring back to their normal position wherein the engaging lugs are over the annular collar, but out of contact therewith. 25 By virtue of this arrangement, if the instrument were picked up by the horn, the horn would not be removed, but would be retained on the standard by the engagement of the collar against the lugs of the springs. In 30 normal position, however, with the collar and springs out of engagement, there is no metallic connection such as would permit the transmission of vibrations from the standard to the horn. The horn, together 35 with the receiver, may be removed from the standard by pushing back the springs and withdrawing the shank of the horn and the receiver upwardly through the barrel.

The operation of the transmitter and the receiver in this instrument is the same as in customary practice except that with the connections diagrammatically shown in Fig. 4, the receiver is constantly closed across the line. By the proper insertion of a switch, 40 however, it is obvious that the instrument may be arranged so that the receiver may be cut out of the line, and closed on the line as desired. The horn, of course, provides a resonance column over the receiver diaphragm which operates to amplify the sound from the receiver to the degree necessary to make the reproductions audible at a distance from the horn. The relative disposal of the mouth of the horn, which is the 45 auditory outlet of the receiver, and the transmitter, is such that when the operator is in position to speak into the transmitter, his ears are perfectly in front of the auditory outlet of the receiver, and hence in an 50 advantageous position to hear the messages

received. By virtue of this construction, therefore, I secure an instrument wherein the transmitter and the receiver are structurally united in a single instrument which may be conveniently handled in use, and in 55 which the relative disposal of the transmitter and the auditory outlet of the receiver is such as to contribute maximum convenience in the use of the instrument and enable its being employed most effectively. 60 At the same time, this construction provides an assembly of transmitter, receiver and amplifying horn such as prevents or inhibits the transmission to the receiver and to the horn of such vibrations as are competent to 65 produce a harmonic vibration of the receiver diaphragm, or a resonant vibration in the horn. Hence, in conjunction with the convenient relative disposal of parts, this structure provides an instrument which will give 70 a clear reproduction, entirely free from chattering, howling, or other interfering noises.

The receiver horn is designed as to form so that it may best perform its function, and also lend itself to the most convenient manipulation of the instrument. When the head of the operator is in the proper position for using the instrument, it will be seen that the mouth or bell of the horn is directed 75 forwardly toward the auditory organs, while the convolution in the lower wall of the horn provides a space for the operator's nose, thereby preventing the air currents occasioned by the operator's breathing from passing into the horn, and thus protecting 80 the receiver from this influence which might operate to set up casual vibrations therein. The open end of the horn rests in front of the operator's eyes, and the hood or bell of the horn forms an effective shade or shield 85 in proper disposal relative to the transmitter to house and shade a telephotic reproducing screen.

In Figs. 6 and 7, is shown a modified form of the horn and barrel, the same being 90 designed to accommodate a visual screen 27 set in the back of the horn in the line of vision of the operator when his head is in position to use the instrument. In this 95 form, the visual screen provides a transparent window in the rear of the horn through which the operator, while using the instrument, may look for the purpose of seeing a sheet upon which he may be writing, without necessitating his turning his mouth away 100 from the transmitter, as would be necessitated were he compelled to place the writing at one side of the standard. To accommodate the natural line of vision in this use of the instrument, the barrel is cut down at the 105 rear so that its upper edge is sloping as in the fashion shown. With this construction, the hood forms an eye shade for the operator, permitting him to concentrate his entire attention upon his work, without being 110

distracted by irrelevant things within what otherwise would be his zone of vision.

In the use of the device as shown in Fig. 4, in which, as above stated, the receiver is constantly closed across the line, the operator will hear all messages delivered onto the line. When the operator wishes to talk onto the line, he closes switch 6 by pressing inwardly the push button 28. This operates to close the battery on the primary circuit and the secondary circuit through the induction coil. The structure obviously forms a unitary loud speaking instrument which may be transported or moved about in use in its integrity, which is slightly and well balanced in appearance, and which is adapted for use in situations in which the well known desk instrument is commonly employed, being self-sustaining on its base and conveniently handled.

I am aware that the device is obviously susceptible of changes, adaptations and modifications not herein specifically illustrated or described, but still within the scope and spirit of my invention as indicated in the following claims.

What I claim is:

1. In a telephone instrument, the combination of a yieldingly supported horn, and a telephone receiver suspended therefrom with its vibratory portion in operable association therewith.

2. In a telephone instrument, the combination of an amplifying horn, a telephone receiver disposed with its diaphragm in operative relationship thereto, and yieldable connecting members whereby the receiver is supported on the horn.

3. In a telephone instrument, a rigid supporting stand, an amplifying horn, a telephone receiver disposed with its diaphragm in operative association with the horn, and relatively flaccid connecting members for supporting the horn on the stand and the receiver on the horn.

4. In a telephone instrument, the combination of a supporting stand, a transmitter supported thereon, an amplifying horn removably supported on said stand with a portion extending within the latter and a portion disposed exterior thereof in operative association with the transmitter, and a receiver supported on the horn out of contact with the support, and having its vibratory portion operably associated with the horn.

5. A telephone instrument including the combination of a support, a telephone transmitter supported at the upper portion thereof, an amplifying horn carried on the support and having a bell or mouth portion extending from the support above the transmitter, a portion of said bell being transparent, and a telephone receiver operatively associated with said horn.

6. In an instrument for the electrical

transmission of intelligence, a support, a sound transmitting device disposed at the front thereof, a horn having a hood and mouth-portion disposed above the transmitting device and in the line of vision of an operator using the latter, and a visual screen carried by said hood.

7. In a telephone instrument, the combination of a support, a telephone transmitter and receiver mounted thereon, a hood member operably associated with the receiver and disposed above the transmitter, the lower wall of said hood member above said transmitter being formed with a reentrant convolution to permit its being placed in association with the eyes and ears of an operator.

8. A telephone instrument comprising a barrel portion, a transmitter supported on the barrel portion, a receiver supported within the barrel portion, and a horn supported on the barrel portion and having a shank portion extending downwardly thereinto into association with the receiver and a bell portion extending forwardly therefrom in association with the transmitter.

9. In a telephone instrument, the combination of a stand, an amplifying horn supported thereon, a telephone receiver disposed in operative association with the horn, and a yieldable member operatively connecting the horn and the receiver and maintaining the latter out of contact with the horn and the stand.

10. In a telephone instrument, the combination of a support, a receiver horn, interengaging members carried by said horn and said support for retaining the former upon the latter, and a yieldable member supporting said horn on said support with said interengaging members out of contact with each other.

11. A telephone instrument including a stand having a base portion and a barrel portion extending upwardly therefrom, a telephone transmitter supported on the barrel portion, a telephone receiver disposed within the base portion, and a receiver horn supported on the barrel portion and operatively associated with the receiver.

12. A telephone instrument including a stand having a barrel portion, a receiver disposed within the barrel portion, and yieldingly supported from the stand, and a horn supported on the barrel portion and having a bell portion extending outwardly therefrom and a shank portion extending downwardly into operative association with the receiver.

13. A telephone instrument including a stand having a supporting base and a barrel portion extending upwardly from said base, an amplifying horn removably supported on said barrel portion and having a bell portion opening laterally, and a receiver yield-

ingly supported within the stand and in co-operative relationship with the horn.

14. A telephone instrument of the stand type terminating at its upper extremity in a forwardly opening bell or hood portion; a shank portion extending downwardly therefrom, a receiver operably associated with the lower extremity of said shank and yieldably supported within the stand, and a transmit-

ter supported below and adjacent the bell portion.

In testimony whereof I hereunto affix my signature in the presence of two witnesses, this 26th day of November, 1915.

F. E. BENTLEY.
